UNITED STATES PATENT OFFICE.

HERMAN G. VOSHARDT, OF CHICAGO, ILLINOIS, ASSIGNOR TO FRIEDLEY-VOSHARDT CO.,
OF CHICAGO, ILLINOIS, A CORPORATION OF ILLINOIS.

DESIGN FOR A WEATHER-VANE OR LIGHTNING-ROD ORNAMENT.

52,361.

Specification for Design.

Patented Aug. 27, 1918.

Application filed February 28, 1918. Serial No. 219,704. Term of patent 7 years.

To all whom it may concern:

Be it known that I, HERMAN F. VOSHARDT, a citizen of the United States, residing at Chicago, in the county of Cook and State of Illinois, have invented a new, original, and ornamental Design for a Weather-Vane or Lightning-Rod Ornament, of which the following is a specification, reference being had to the accompanying drawing, forming part thereof.

The figure is a side view of a weather vane or lightning rod ornament, showing my new design.

I claim:

The ornamental design for a weather vane or lightning rod ornament, as shown.

HERMAN F. VOSHARDT.
